BARRING MECHANISM FOR BUTTONHOLE
SEWING MACHINES

Alfred R. Wood, Bridgeport, Conn., assignor to
The Singer Manufacturing Company, Elizabeth,
N. J., a corporation of New Jersey

Application June 22, 1948, Serial No. 34,374

4 Claims. (Cl. 112—73)

1

This invention relates to sewing machines and more particularly to sewing machines of the buttonhole type having mechanism whereby the length of the stitches is automatically increased at the end or ends of the buttonhole upon cessation of the feeding movements of the work-clamp for the purpose of producing barring stitches.

The present invention is an improvement over the barring mechanism disclosed in my prior Patent No. 2,411,493, issued Nov. 19, 1946, and it has for its primary object to provide a barring mechanism in which the components thereof remain mutually operatively connected throughout the entire cycle of operation.

In the mechanism disclosed in my prior patent there is a complete separation of certain of the members in the mechanism during the time the said members are being shifted to effect a change in the amplitude of vibration of the needle. The separation of the parts renders the mechanism susceptible of faulty operation particularly during the reconnecting of the parts. This results from the fact that the parts or members to be mutually connected may not be in proper register relative to each other and, obviously, when this occurs the instantaneous recoupling of the members is impossible. The fact that the members of the present barring mechanism are not separated at any time during the machine cycle renders the same more positive in its action, without any chance of defective operation incident to the interruption of the operative relationship of the parts comprising the mechanism. With my improved barring mechanism, change in the amplitude of vibration of the needle is instantaneous and positive, regardless of when the mechanism is actuated in the stitching cycle.

Further advantages and beneficial results in operation will be apparent from the following description of an illustrative embodiment of my invention taken in connection with the accompanying drawings, in which:

Fig. 1 is a right side elevational view of a portion of a buttonhole sewing machine embodying the present invention, the head of the machine being sectioned to disclose the needle-bar vibratory frame.

Fig. 2 is a top plan view of the bracket-arm of the sewing machine.

Fig. 3 is an enlarged top plan view of the needle-bar vibrating mechanism and the bar-stitch counting device, showing the relative positions of the component parts thereof when the machine is producing the side stitches of the buttonhole.

2

Fig. 4 is a view similar to Fig. 3, but with the bar-stitch counting mechanism removed to show more distinctly the details of the needle-bar vibrating mechanism.

5 Fig. 5 is a view similar to Fig. 3, with the components of the needle-bar vibrating mechanism in their relative positions at the end of the side-stitching operation and just before the parts are shifted into their barring position.

10 Fig. 6 represents an enlarged vertical sectional view taken substantially along the line 6—6, Fig. 2, but with the parts located in the position shown in Fig. 5.

15 Fig. 7 is a top plan view similar to Fig. 3, but with the needle-bar vibrating mechanism in position to produce the relatively long barring stitches and the bar-stitch counting device operating to determine the number of stitches comprising the bar.

20 Fig. 8 represents an enlarged vertical sectional view taken substantially along the line 8—8, Fig. 2.

25 Fig. 9 is a view similar to Fig. 7, but with the bar-stitch counting device advanced to a position in which it is about to release the needle-bar vibrating mechanism from its barring position, so that said vibrating mechanism can be spring-returned to its side-stitching position.

30 Fig. 10 represents an enlarged horizontal sectional view taken substantially along the line 10—10, Fig. 1, showing in elevation the cam for effecting an interruption in the feed of the work-clamp and for shifting the needle-bar vibrating mechanism for side-stitching to bar-stitching position.

35 Fig. 11 represents a horizontal sectional view taken substantially along the line 11—11, Fig. 1.

Fig. 12 represents an enlarged sectional view taken substantially along the line 12—12, Fig. 5.

40 Fig. 13 represents a sectional view taken substantially along the line 13—13, Fig. 3.

Fig. 14 represents a sectional view taken substantially along the line 14—14, Fig. 7.

45 Referring more in detail to the drawings, the machine chosen for the purposes of the present disclosure is constructed in accordance with that shown in my prior patent above mentioned. Only sufficient of the structural details of the machine are illustrated in the accompanying drawings as are needed for an understanding of the present invention. The sewing machine has a frame including a bed 11 from which rises a standard (not shown) of the bracket-arm 12 terminating in a head 13. Journaled in the bracket-arm 12 is a mainshaft 14 connected at its rear end,

by spur-gears 15, 16, 17 and 18, Fig. 2, to a countershaft 19 driven by a belt adapted to run upon a nest of pulleys 20 carried by the counter-shaft 19. For a detailed description of the main-shaft drive, reference may be made to my U. S. Patent No. 2,338,611, issued Jan. 4, 1944.

The stitch-forming mechanism of the machine includes an eye-pointed thread-carrying needle 21, Fig. 1, carried in the lower end of a needle-bar 22 journaled for endwise reciprocatory movements in spaced bearings formed in a vibratory needle-bar-gate 23 supported upon pintles 24 within the head 13. The needle-bar 22 may derive its reciprocatory movements from the main-shaft 14 by means of any usual or suitable connections therewith. Cooperating with the needle in the formation of stitches is any suitable form of loop-taker (not shown) located beneath the bed 11.

The work to be buttonholed is adapted to be held in a work-clamp, Fig. 1, comprising the usual lower work-plate 25 and the upper clamp-foot 26. The work-clamp is slowly moved in step-by-step fashion under the endwise reciprocatory and laterally vibratory needle 21, first away from the machine-frame standard (to the left in Fig. 1) and then towards the standard to cause the first and second rows of side zigzag stitches to be laid side by side in the work. The work-clamp derives its step-by-step movements from the usual feed-cam (not shown) carried on the lower end of a vertical feed-shaft 27 journaled in the machine-frame. The connections between the work-clamp and the feed-cam, and the manner in which the feed-cam is intermittently rotated, is fully illustrated and described in my above mentioned prior Patent No. 2,411,493. Included in the mechanism for intermittently rotating the feed-cam is a one-way clutch. Automatically controlled means are provided for rendering the one-way clutch ineffective during certain periods in the buttonholing cycle so that the step-by-step movements of the work-clamp relative to the laterally vibratory needle can be suspended for a short time in order that a suitable number of barring stitches may be made at the ends of the buttonhole. The period of the suspension of the one-way clutch is determined by the customary bar-stitch counting mechanism later to be described.

The automatically controlled means for rendering the one-way clutch ineffective comprises a spline 28 preferably extending the entire length of the feed-shaft 27 and operatively connected at its lower end to the clutch so that the raising of the spline will shift the clutching elements of the clutch into an ineffective position. The spline is shifted up and down relative to the feed-shaft 27 by means of a collar 29 (Figs. 6 and 8) slidably mounted on the feed-shaft and secured preferably by screws 30 to the spline 28. Formed in the collar 29 is an annular recess 31 entered by a roller 32 carried on the inner end of a lifting lever 33 freely pivoted on a fulcrum-stud 34 journaled in spaced bearing lugs 35 (Fig. 1) integral with the wall of the bracket-arm 12. The lifting lever 33 is adapted to be actuated in a clockwise direction (Fig. 8) to raise the spline 28 and thereby render the one-way clutch ineffective, by a vertically disposed rocker 36 fixed on the fulcrum-stud 34. The lower end of the vertically disposed rocker is in peripheral contact with a feed-cam release actuating element in the form

of a two-lobe cam 37 (Fig. 10) which is fast upon the feed-shaft 27. Each lobe of the cam 37 is cut with a gradual rise 38 terminating in a drop-off 39 so that, as the feed-shaft 27 is turned, the lower end of the rocker 36 is gradually swung outwardly in opposition to a coil-spring 40 (Figs. 1 and 6), which is anchored at one end to an arm 41 on the bracket-arm 12 and connected at its other end to the lower end of a lever-arm 42 pinned to the fulcrum-stud 34. As the outwardly swinging motion of the rocker 36 is continued, a pawl-lever 43 (Figs. 1, 5, 6 and 8) pivotally carried on the rocker 36 is raised relative to the lifting lever 33 until a step or shoulder 44 formed on the pawl-lever 43 moves above the level of the upper edge of the lifting lever 33 when, under the action of the spring-wire 45, the pawl-lever 43 snaps into a substantially vertical position, i. e. from the position shown in Fig. 3 to that shown in Fig. 5, thereby connecting the lifting lever 33 with the rocker 36. As the feed-shaft 27 continues to turn and the drop-off of the cam 37 passes by the lower end of the rocker 36, the rocker snaps inwardly under the influence of the coil-spring 40 and into a position determined by an adjustable stop 46 carried by the rocker 36. This rapid inward motion of the rocker 36, through the pawl-lever 43 and the lifting lever 33, raises the spline 28 and this forces the clutch-elements of the one-way clutch into ineffective position. As explained in my above mentioned Patent No. 2,411,493, when the clutch-elements are in their ineffective position, the feed-shaft is not intermittently rotated, but remains stationary. Thus the work-clamp is not shifted relatively to the laterally vibratory needle.

It will be understood that during the step-by-step movements of the work-clamp the needle 21 is vibrated transversely of the line of movement of the work-clamp. To provide for this, the needle-bar 22 is endwise journaled in the needle-bar-gate 23 supported for vibratory movements on the pintles 24. Connected to the upper end of the needle-bar-gate 23 is one end of an endwise extensible link 46 adjustably connected at its other end to a vibratory lever 47 fulcrumed on a pivot-stud 48 threaded into the bracket-arm 12. The vibratory lever 47 is connected by a link 49 to one end of an actuating rock-lever 50 supported in the slotted upper portion of a fulcrum-disk 51 seated for free turning movement in a socket 52 formed in one end of a fulcrum-carrying slide 53 slidable in a guideway 54 formed in the bracket-arm 12. A plate 55 retains the actuating rock-lever 50 and the fulcrum-disk 51 in proper assembled relation in the fulcrum-carrying slide 53. The other end of the actuating rock-lever 50 is connected by a link 56 to one end of an oscillatory actuator-lever 57 (Fig. 4) fulcrumed on a stud 58 threaded into the bracket-arm 12. A stud 59 connecting the link 56 to the oscillatory actuator-lever 57 is extended at its lower end and has journaled thereon a roller 60 (Fig. 8), which tracks a cam-groove 61 formed in an operating driving element or cam 62 fast upon the counter-shaft 19, the speed of rotation of which is one-half that of the arm-shaft 14 during the normal buttonholing cycle. The stud 50' (Figs. 7 and 8) is provided with a roller at its lower end, which roller tracks a guide-slot 51' formed in an angle-bracket 52' secured to the side of the bracket-arm 12. It will be understood from the above description that rotation of the cam

62 will cause the actuator-lever 57 to oscillate about its fulcrum-stud 58, thus transmitting vibratory movements to the needle-bar-gate 23 through the connections 56, 50, 49, 47 and 46. Adjustment of the length of the link 46 provides for properly centralizing the stitches relative to the usual buttonhole slit. Adjustment of the end of the link 46 on the vibratory-lever 47 permits regulation of the amplitude of vibration of the needle-bar-gate 23 and hence the length of the stitches forming the buttonhole.

To effect the production of the barring stitches during the time that the step-by-step movements of the work-clamp are suspended, the amplitude of the lateral vibrations of the needle is customarily increased preferably to substantially twice that of the lateral vibrations of the needle during the formation of the side stitches. The improved means by which the amplitude of the vibration of the needle can be increased operates to effect a shift of the fulcrum-disk 51 lengthwise of the guideway 54; the result being to shift the fulcrum-axis of the actuating rock-lever 50 and thereby change the effective lengths of the respective lever-arms of the rock-lever 50. To this end, the rocker 36 is provided with an extension 63 (Figs. 3, 5, 7 and 9) having pivoted to its free end a latch 64 formed with a vertical shoulder 65 (Figs. 13 and 14); the latch 64 being biased downwardly by a coil-spring 66 into cooperative relation with one end of a slide-shifting lever 67 fulcrumed intermediate its ends on a pivot-stud 68. The other end of the slide-shifting lever 67 is forked to engage a roller 69 journaled on a pin 70 extending upwardly from the fulcrum-carrying slide 53. As shown in Fig. 8, the fulcrum-carrying slide 53 is provided with a second roller 71 engaged by the forked upper end of a lever 72 pivoted on the fulcrum-stud 34 and having connected to its lower end the coil-spring 73. The coil-spring 73 is provided to yieldingly maintain the fulcrum-carrying slide 53 in its side-stitching position, shown for example in Fig. 8. From the above, it will be understood that as the feed-shaft is intermittently rotated to impart step-by-step movements to the work-clamp, the cam 37 likewise turns and causes the rocker 36 to turn on its supporting fulcrum-stud 34 (counterclockwise in Fig. 8). As the rocker 36 continues to turn, the rocker-extension 63 moves inwardly, carrying with it the latch 64, which latch slides across one end of the slide-shifting lever 67 (Fig. 3) until its shoulder 65 moves beyond the edge of the lever 67. The spring 66 then pulls the latch 64 downwardly so that the slide-shifting lever 67 becomes latched to the rocker 36, as shown in Fig. 5. The latching together of the lever 67 and the rocker 36 occurs just before the cam 37 travels to the point where the lower end of the rocker 36 is in engagement with the high point of the cam-lobe. When the cam 37 rotates to the point where one of its drop-offs 39 passes by the lower end of the rocker 36, the latter snaps inwardly under the influence of the coil-spring 40 into a position determined by the adjustable stop 46. During this rapid movement of the rocker 36 the fulcrum-carrying slide is quickly shifted from its side-stitching position (Fig. 3) to its bar-stitching position (Fig. 7). As previously explained, the rapid drop-off of the rocker 36 from the high point on the cam 37 also effects a shift of the clutch-releasing spline 28 into a position such that the feed-clutch is

rendered ineffective and the step-by-step movements of the work-clamp are terminated. It will be appreciated that the termination of the feeding movements of the work-clamp and the increase in the amplitude of needle-vibration is effected simultaneously, without any hesitation or interruption on the part of either mechanism. This is desirable for the reason that the barring stitches are formed in a neatly stacked arrangement at the end of the buttonhole and are not dispersed in any form of a spread pattern. It will be understood that the shifting from side-stitching position to bar-stitching position can be accomplished with facility in any position of the parts for the reason that the actuating rock-lever 50 is continuously in engagement with its fulcrum-disk 51 and that, in changing from side-stitching position to bar-stitching position, the fulcrum disk 51 is merely shifted longitudinally of the guideway 54 by the rapid movement of the rocker 36.

The number of stitches included in each bar is determined by a suitable bar-stitch counting mechanism substantially the same in design as that disclosed in my previously mentioned Patent No. 2,411,493. The present bar-stitch counting mechanism comprises a ratchet-wheel 74 mounted for limited turning movement on the upper end of the fulcrum-stud 58 (Figs. 4 and 9). Interposed between the head of a screw 75 threaded into the end of the fulcrum-stud 58 and the top of the fulcrum-stud 58 is a disk 76 resting upon a coil-spring 77 having one of its ends anchored in a hole 78 formed in the ratchet-wheel 74. The coil-spring 77 functions to bias the ratchet-wheel 74 in a clockwise direction, as seen in Fig. 1, against an adjustable stop 79 depending from a cover-plate 80 and adapted to be clamped in desired set position by a thumb-nut 81. That portion of the ratchet-wheel 74 which is normally biased into contact with the adjustable stop 79 comprises an arcuate plate-member 82 (Fig. 9) clamped for circular adjustment by screws 83 in an annular recess 84 formed in the upper face of the ratchet-wheel 74.

The ratchet-wheel 74 is adapted to be advanced in a counterclockwise direction, as viewed in Figs. 4 and 9 by an actuating pawl 85 pivotally mounted on an extension 86 of the oscillatory actuator-lever 57; the actuating pawl 85 being biased into engagement with the teeth on the ratchet-wheel 74 by a leaf-spring 87. Cooperating with the actuating pawl 85 in advancing the ratchet-wheel 74 is a detent-pawl 88 which functions to preclude retrograde turning of the ratchet-wheel. It will be understood that as the actuator-lever 57 is oscillated about its fulcrum-stud 58 by the cam 62, the actuating pawl 85 is operated in such a manner as to engage and advance the ratchet-wheel tooth-by-tooth and that the detent-pawl 88 maintains the ratchet-wheel in its various steps of advancement. After the number of barring stitches to which the adjustable stop 79 is set has been produced, during which time the ratchet-wheel 74 is being advanced by the actuator-pawl 85, a trip-plate 89 adjustably secured in the recess 84 formed in the ratchet-wheel 74 is brought into engagement with a pin 90 depending from a cross-lever 91 which is pivoted intermediate its ends on a stud 92 threaded into the cover-plate 80. After engagement of the pin 90 by the trip-plate 89, further turning of the ratchet-wheel 74, under the action of the actuating pawl 85, swings the cross-lever 91 about its pivot 92 in the direction

indicated by the arrow in Fig. 5, thus moving its free end into contact with the upstanding tail portion of the pawl-lever 43. Continued swinging movement of the cross-lever 91 turns the pawl-lever 43, against the action of the spring 45, thereby moving its shoulder 44 from its position vertically above the lifting lever 33 to the position indicated in dotted lines in Fig. 12. Depending from the cross-lever 91 is a release-pin 93 to which is pivoted, adjacent the cross-lever 91, a trip-finger 94 slidable between two guide pins 95 and formed at its free end with a wedge or inclined face 96 disposed to slide beneath the latch 64. After the cross-lever 91 has moved the pawl-lever 43 out of operative relation with the lifting lever 33, continued movement of the cross-lever will move the trip-finger 94 in a direction to cause its wedge-shaped end to slide beneath the latch 64 and raise it about its pivot to release the slide-shifting lever 67, permitting the coil-spring 73 to rapidly return the fulcrum-carrying slide 53 to its side-stitching position. During the release of the latch 64, the lower end of the release pin 93 is adapted to move into contact with the limb 97 of a pawl 98 (Fig. 9) journaled on a ball-stud 99 threaded into the upper end of the rocker 36. Further turning of the cross-lever 91, in response to the step-by-step advance of the ratchet-wheel 74, swings the pawl 98 about the ball-stud 99 causing the limb 100 of the pawl 98 to release a projection 101 on a reclutching lever 102 pivoted at 103 on the bracket-arm 12. When the projection 101 is released, the reclutching lever 102, under the influence of a coil-spring 104, snaps from bar-stitching position (Fig. 9) to side-stitching position (Fig. 3). In moving from bar-stitching position to side-stitching position, a cam-projection 105 on the reclutching lever 102 engages a tail-member 106 on the ratchet-wheel actuating pawl 85 and shifts the actuating pawl, in opposition to the leaf-spring 81, from its effective position shown in Fig. 9 to its ineffective position shown in Figs. 3 and 5. As shown in Fig. 5, this shifting of the actuating pawl 85 causes it to move into engagement with the detent-pawl 88 and shift the latter against its spring 107 out of engagement with the teeth on the ratchet-wheel 74. When the ratchet-wheel is thus released from the detent-pawl, the spring 77 biases the ratchet-wheel in a clockwise direction (Fig. 9) and against the stop 79, whereby the bar-stitch counting mechanism is reset for the subsequent barring operation.

In order to resume the side-stitching operation at the completion of the bar-stitching operation, it is required that the clutch-releasing spline 28 be lowered to permit the clutch-members to assume their wedging relation between the clutch-drum and the live clutch spider, in the manner disclosed in my previously mentioned Patent No. 2,411,493. In the present case, the reclutching lever 102 is fitted with a depending adjustable abutment-screw 108, and this screw is adapted to strike the upper end of a spline-depressing bell-crank lever 109 (Fig. 6) when the reclutching lever is released from the pawl 95 at the completion of the barring operation. As the bell-crank lever 109 turns under the blow of the abutment-screw 108, the horizontal limb of the bell-crank lever (Fig. 6) moves downwardly and a roller 110 carried at the free end of the horizontal limb of the lever 109 and disposed in the annular recess 31 of the collar 29 slides the collar downwardly on the feed-shaft 21. The collar, through the spline

28, renders the clutch again effective to turn the feed-cam.

From the above description, it will be understood that I have invented an improved barring mechanism in which a change in the amplitude of vibration of the sewing machine needle is effected by merely shifting the fulcrum axis about which one of the members of the mechanism is oscillated. The fulcrum for said member is carried on a slide which is automatically moved in one direction and spring returned after the requisite number of barring stitches is made. It will be appreciated that by supporting the rock-lever 50 in a fulcrum disk 51 such that the rock-lever is never separated from the fulcrum disk, the mechanism to change the amplitude of vibration of the needle can be operated anytime in the buttonholing cycle. Its action in changing the amplitude of needle vibration is instantaneous, it can be performed without a clashing of the parts and with the expenditure of a minimum of effort.

Having thus set forth the nature of the invention, what I claim herein is:

1. A buttonhole sewing machine having stitch-forming mechanism including a reciprocatory and laterally vibratory needle and barring mechanism for changing the amplitude of vibration of the needle to sew barring stitches at an end of the buttonhole, said barring mechanism comprising, an operating driving element, an actuating rock-lever operatively connected to said driving element and to said needle, a shiftable fulcrum-support for said actuating rock-lever having a side-stitching position and a bar-stitching position, a fulcrum-carrying slide to which said fulcrum-support is attached, a spring for biasing said fulcrum-carrying slide into one of its positions, releasable connections for moving said slide and thereby said fulcrum-support to the other of its positions against the action of said spring, and trip means for separating said releasable connections and permitting said spring to return said slide to its other position.

2. A buttonhole sewing machine having stitch-forming mechanism including a reciprocatory and laterally vibratory needle and barring mechanism for changing the amplitude of vibration of the needle to sew barring stitches at an end of the buttonhole, said barring mechanism comprising, an operating driving element, an actuating rock-lever operatively connected to said driving element and to said needle, a shiftable fulcrum-support for said actuating rock-lever having a side-stitching position and a bar-stitching position, a fulcrum-carrying slide to which said fulcrum-support is attached, a spring for biasing said fulcrum-carrying slide in a direction to move said fulcrum-support into its side-stitching position, cam-controlled releasable connections for moving said slide and thereby said fulcrum-support to bar-stitching position against the action of said spring, a bar-stitch counting device for controlling the number of stitches in the bar, and trip means associated with said bar-stitch counting device for separating said releasable connections and permitting said spring to return said fulcrum-support to its side-stitching position.

3. A buttonhole sewing machine having stitch-forming mechanism including a reciprocatory and laterally vibratory needle and barring mechanism for changing the amplitude of vibration of the needle to sew barring stitches at an end of the buttonhole, said barring mechanism comprising, an operating driving element, an actuating rock-lever operatively connected to said driving ele-

ment and to said needle, a support for said actuating rock-lever including a fulcrum-disk slotted for slidably engaging said actuating rock-lever, a supporting slide on which said fulcrum-disk is rotatably mounted, and operative connections for shifting said fulcrum-supporting slide.

4. A buttonhole sewing machine having stitch-forming mechanism including a reciprocatory and laterally vibratory needle and barring mechanism for changing the amplitude of vibration of the needle to sew barring stitches at an end of the buttonhole, said barring mechanism comprising, a rotary driving element, an actuating rock-lever operatively connected to said driving element and to said needle, a fulcrum-carrying slide supported for endwise movement and having a socket formed

therein, a fulcrum-disk rotatably seated in said socket and formed with a slot to slidably engage said actuating rock-lever, a spring for biasing said fulcrum-carrying slide in one direction, and operative connections for shifting said fulcrum-carrying slide in the opposite direction.
